FOUNTAIN PEN

Manuel Portus Ribas, Torello, Spain

Application June 8, 1956, Serial No. 41,821

Term of patent 14 years

Claims priority, application Spain March 16, 1956

(Cl. D74—17)

FIG. 1

FIG. 2

FIG. 3

FIG. 4

FIG. 5

FIG. 6

FIG. 7

FIG. 8

Fig. 1 is a front elevational view of a fountain pen showing my new design as it appears in closed position; Fig. 2 is a side elevational view thereof;

Fig. 3 is a rear elevational view;

Fig. 4 is a top plan view thereof;

Fig. 5 is a front elevational view of the fountain pen as it appears in writing position with the cap remounted on the other end of the barrel;

Fig. 6 is a side elevational view of the fountain pen as shown in Fig. 5;

Fig. 7 is a rear elevational view; and

Fig. 8 is a bottom plan view thereof.

I claim:

The ornamental design for a fountain pen, as shown.
